H. HEIMENDINGER

SIGNAL DEVICE FOR ROAD CROSSINGS

Filed Oct. 24, 1922

Inventor
Henry Heimendinger

By his Attorneys

C. L. D. & Co.

UNITED STATES PATENT OFFICE.

HENRY HEIMENDINGER, OF LAKE CHARLES, LOUISIANA.

SIGNAL DEVICE FOR ROAD CROSSINGS.

Application filed October 24, 1922. Serial No. 596,594.

To all whom it may concern:

Be it known that I, HENRY HEIMENDINGER, a citizen of the United States, and residing at Lake Charles, in the parish of Calcasieu and State of Louisiana, have invented certain new and useful Improvements in Signal Devices for Road Crossings, of which the following is a specification, such as will enable those skilled in the art to which it applies to make and use the same.

This invention relates to signal devices and particularly to devices of this class designed for use in connection with a railway where a road or thoroughfare crosses the same, and the object of the invention is to provide a signal device of the class and for the purpose specified which is in circuit with the tracks of a railway whereby a train approaching a road crossing the tracks of a railway will automatically actuate signal devices to signal motorists, vehicle drivers or others of the approach of a train; a further object being to provide a signal device or devices of the class specified which will also normally indicate that the tracks of the railway are clear and the same may be crossed without danger; and with these and other objects in view the invention consists in a signal device of the class and for the purpose specified which is simple in construction, automatic in operation and constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a perspective view diagrammatically illustrating the use of my improved signal devices;

Fig. 2 a detail front view of one of my improved signal devices with part of the construction broken away and in section; and,

Fig. 3 a diagrammatic sectional view partially on the line 3—3 of Fig. 2 and showing the interior structure of one of my improved signal devices.

In Fig. 1 of the drawing I have shown for the purpose of illustrating one use of my invention, a track 10 of a railway and at 11 a road crossing such track, and at 12 I have shown two of my signal post constructions located at the opposite sides of the

track of a railway and on the sides of the road 11.

The signal posts comprise in the construction shown bases 13, standards 14 and box-shaped signal heads 15, the front faces of which are open, and said openings are closed by transparent or translucent panels 16, divided centrally into top and bottom members 17 and 18, the top member being preferably colored green and provided with the word "Go" and the letters R X R thereon, while the member 18 is preferably colored red and is provided with the word "Stop" and the letters R X R thereon. The words Go and Stop may appear in any desired manner but will preferably appear in white letters on the green and red backgrounds and will be visible both in the daytime and at night.

Mounted in the casing 15 or head of each of the signal posts is an electric lamp bulb 19 placed in circuit with a suitable source of electrical supply through wires 20 which connect with the socket for the bulb 19, and pivotally mounted in the casing 15 and adjacent to the opposite ends thereof are arms 21 joined by a cross rod 22 with which is coupled a floating core 23 of a solenoid 24 by means of a link 21^a and to the ends of the arms 21 is pivotally mounted a shutter plate 25 which is adapted to move upwardly and downwardly in the casing in juxtaposition to the transparent or translucent panel, or the separate members 17 and 18 thereof, and this shutter normally covers the member 18 and the light from the bulb 19 passes through the member 17 and the letters formed therein to show a green light with the word Go and letters R X R appearing therein. The solenoid 24 is placed in circuit with the rails 90 of the track 10 by circuit wires 26 and the circuit to the solenoid is closed through the rails of the track 10 in the usual manner by the locomotive or car passing thereover, or the solenoid may be placed in the usual block 100 circuit of the track or tracks of the railway and be automatically operated in the manner of actuating any signal device commonly employed in such circuits. The solenoid is also diagrammatically illustrated at 24^a in Fig. 3.

From the foregoing it will be understood that my improved signal post normally illuminates the member 17 of the transparent or translucent panel 16, which is preferably colored green, and indicates that the track or tracks of a railway to be crossed is clear to a motorist or others approaching

such railroad crossing. In the event of a locomotive or car on the track or tracks of the railway approaching a road provided with my signal devices, however, the same 5 will be automatically actuated by the completion of the circuit to the solenoid 24 of the signal post to move the shutter 25 thereof upwardly to cover the member 17 and expose the member 18 of the transparent 10 panels 16 and a red light will appear in the signal posts as well as the word Stop and R X R indicating the approach to a railroad crossing and also designating that a train or locomotive is about to cross the roadway.

15 I am well aware of the fact that signal devices have been employed endeavoring to produce the result produced by the use of my improved signal post or posts, but to my knowledge the desired result has not been 20 accomplished in a simple and yet positive manner to clearly and definitely warn motorists or others of their approach to a railroad crossing, and with my improvement I not only give a warning or danger signal 25 but also a signal of clear traffic at a railroad crossing, it being understood that normally the signal Go with the letters R X R will appear and be illuminated in the signal posts employed. It will also be understood 30 that my invention is not limited to the specific details of construction herein shown and described for carrying my invention into effect, and various changes therein and modifications thereof may be made, within 35 the scope of the appended claims, without departing from the spirit of my invention or sacrificing its advantages, and it will also be understood that while I have shown a single track of a railway that the invention 40 may apply to a railway of any number of tracks where a road or thoroughfare crosses the same, and my improved signal posts may be of any general form and construction but are preferably located in the manner shown 45 and described.

Having fully described my invention, what I claim as new and desire to secure by Letters Patent, is:-

1. A railroad crossing signal of the class 50 described comprising a suitable standard provided in the top portion thereof with a head in one face of which is mounted an exposed translucent plate, means within said head for illuminating said plate, said plate being provided with differently colored signal elements, means positioned between said illuminating means and said plate for controlling the signal elements of said head, and means for automatically operating said 55 last named means.

2. A railroad crossing signal of the class 60 described comprising a suitable standard provided in the top portion thereof with a head in one face of which is mounted an exposed translucent plate, means within said

head for illuminating said plate, said plate being provided with differently colored signal elements, means positioned between said illuminating means and said plate for controlling the signal elements of said head, and means in circuit with the block system 70 of a railway for automatically controlling the operation of said last named means.

3. A railroad crossing signal of the class 75 described comprising a suitable standard provided in the top portion thereof with a head, one face of said head being provided with differently colored signal elements, means within said head for illuminating said signal elements, and a shutter device 80 positioned between said illuminating means and said signal elements and cooperating with said signal elements for controlling the operation thereof.

4. A railroad crossing signal of the class 85 described comprising a suitable standard provided in the top portion thereof with a head, one face of said head being provided with differently colored signal elements, means within said head for illuminating 90 said signal elements, a shutter device positioned between said illuminating means and said signal elements and cooperating with said signal elements for controlling the operation thereof, and a solenoid in circuit 95 with a block system of a railway for automatically actuating said shutter device.

5. A railroad crossing signal of the class 100 described comprising a suitable standard provided in the top portion thereof with a head, one face of said head being provided with differently colored signal elements, means within said head for illuminating 105 said signal elements, a shutter device positioned between said illuminating means and said signal elements and cooperating with said signal elements for controlling the operation thereof, a solenoid in circuit with a block system of a railway for automatically 110 actuating said shutter device, the circuit to said illuminating means being normally closed.

6. A railroad crossing signal of the class 115 described comprising signal posts adapted to be mounted at the right hand side of a roadway in juxtaposition to the track of a railway crossing said roadway, and at the opposite sides of said track, said signal posts being provided with designated go and stop signals, means for illuminating said signals, means positioned between said signals and illuminating means for automatically controlling said signals, said means being in circuit with a block system of the railway. 120

7. A railroad crossing signal of the class 125 described comprising signal posts adapted to be mounted at the right hand side of a roadway in juxtaposition to the track of a railway crossing said roadway, and at the opposite sides of said track, said signal posts 130

- being provided with designated go and stop signals, means for illuminating said signals, means positioned between said signals and illuminating means for automatically controlling said signals, said means being in circuit with a block system of the railway, and said illuminating means being in a normally closed circuit. 45
- 5 8. A signal device of the class described comprising a box-shaped casing mounted upon a suitable standard, the front face of said casing being closed by a translucent panel provided with top and bottom and differently designated signal elements, a shutter device movably mounted in said casing rearwardly of said translucent panel and normally in position to expose one of the signal elements of said casing, and means in said casing for illuminating said signal elements. 50
- 10 9. A signal device of the class described comprising a box-shaped casing mounted upon a suitable standard, the front face of said casing being closed by a translucent panel provided with top and bottom and differently designated signal elements, a shutter device movably mounted in said casing rearwardly of said translucent panel and normally in position to expose one of the signal elements of said casing, and means in said casing for illuminating said signal elements. 55
- 15 11. A signal device of the class described comprising a box-shaped casing mounted upon a suitable standard, the front face of said casing being closed by a translucent panel provided with top and bottom and differently designated signal elements, a shutter device movably mounted in said casing rearwardly of said translucent panel and normally in position to expose one of the signal elements of said casing, means in said casing for illuminating said signal elements, and means for automatically moving said shutter device into position to expose the other of said signal elements, said means being in circuit with the block system of a railway and involving a solenoid mounted in said casing. 60
- 20 12. A signal device of the class described comprising a box-shaped casing mounted upon a suitable standard, the front face of said casing being provided with a translucent panel provided with top and bottom differently designated signal elements, a shutter device mounted to move upwardly and downwardly in said casing in juxtaposition to said signal elements and normally exposing one of said signal elements, and means in said casing for illuminating said signal elements. 65
- 25 13. In testimony that I claim the foregoing as my invention I have signed my name in presence of the subscribing witnesses this 70
- 30 17th day of October, 1922. 75
